ABSTRACT

A system for detecting fine detail of large objects with high energy particles in which spatially coded masks are located at a plurality of positions between the object and a detecting system. The apertures in the masks are much larger than the wavelength of the high energy particles and the detector, such as a film, detects a hologram-like shadowgraph which is subsequently developed and the image reconstructed therefrom by means of light from a substantially monochromatic source.

11 Claims, 4 Drawing Figures

HIGH ENERGY SPATIALLY CODED IMAGE DETECTING SYSTEMS

BACKGROUND OF THE INVENTION

Apparatus for determining the location and condition of structures and/or organs in living bodies by detecting high speed particles emanating from regions of the body which have selectively absorbed radioactive compounds requires substantial exposure of the body to potentially harmful radiation and, hence, apparatus which reduces the dosage required to obtain an image of the structure or organ of sufficient definition and intensity to permit accurate diagnosis of the condition and location of the structure or organ is of paramount importance. Such definition is also a function of the length of time during which the body can as a practical matter be retained in an immobile position since movement of the body will cause substantial reduction in definition of the reconstructed image.

SUMMARY OF THE INVENTION

This invention provides for a spatially coded pattern from a source of high energy radiation such as, for example, living tissue which has assimilated a radioactive pharmaceutical which is spatially coded, for example, by passing through a plurality of apertured mask zone plates positioned at spaced locations between the living tissue object and a detector.

The term "zone plate", as used throughout the specification and claims, means a structure through which radiation passes in selected regions to produce a beam of radiation having different amplitude levels in different regions of the cross section of the radiation beam passing through the zone plate. A "Fresnel zone plate" means a zone plate in which the cross-sectional pattern has a predominant component comprising at least a portion of the Fresnel zone pattern.

The apertures in the masks, which are defined as those regions of the mask substantially transparent to high energy level radiation, have widths many times the wavelength of the radiation to be detected so that radiation passing through the apertures is substantially undiffracted and the resulting shadowgraph detected by the detector constitutes a spatially coded shadowgraph pattern from which an image of the object may be derived.

The term "radiation energy level", as used throughout the specification and claims, means the energy level of individual packets of photons of radiant energy, said level being directly related to the inverse of its wavelength by Planck's constant. The term "high energy level radiation", as used throughout the specification and claims, means radiation having an energy level higher than the energy level of radiation in the visible spectrum. The upper limit of the visible spectrum is hereby defined as having a 1000 Angstrom free space wavelength.

The shadowgraph produced by the spatially coded pattern has its spatial frequency components improved over a wide range of spatial components so that large objects, for example the entire lung cavity of the patient, can be detected in great detail. More specifically, such a system having improved match of the spatial frequency components of the object to the spatial frequencies detecting and image production system comprises two zone plates which are off-center sections of a Fresnel zone pattern. One zone plate is positioned ad-

jacent the object and may be referred to as the object zone plate. A second zone plate is positioned between one-quarter and three-quarters of the distance from the object zone plate to the shadowgraph detecting surface and, preferably, is positioned substantially equidistant between the object zone plate and the shadowgraph detecting surface which may hereinafter be referred to as the shadowgraph plane.

Further in accordance with this invention, the aperture sizes and locations of the two zone plates are preferably such that straight lines extend from a point substantially at the center of the shadowgraph plane through all corresponding locations of the zone plates. To accomplish this, for example, the zone plate positioned substantially equidistant between the detecting surface and the object zone plate has the apertures thereof identical to the apertures of the object zone plate except that the apertures in the equidistant zone plate are one-half the size of the apertures in the object zone plate.

The efficiency of the detecting process is preferably increased by converting the radiation from high energy level radiation to radiation within the visible spectrum which is then detected by any desired means such as, for example, a recording film.

This invention further contemplates the use of a coding system in an image reproduction system in which the shadowgraph recorded on the film is reduced in size one to two orders of magnitude by a photo reduction process. The shadow spacings will diffract radiation in the visible spectrum from a monochromatic source passing therethrough. More specifically, for example, if the largest aperture width of the zone plate adjacent the object is approximately one millimeter, the number of rings is 50 to 60, and the narrowest aperture width spacing is one-third of a millimeter, then the equidistant zone plate projects shadowgraph line pair spacings of less than a millimeter on the film and reduction in size by photo-optical techniques on the order of 20 to 1 produces line pairs in the red regions of the visible spectrum so that monochromatic light from a conventional laser source having a wavelength in the red portion of the spectrum may be effectively diffracted.

In accordance with this invention, diffraction efficiency may be further increased by bleaching the film to produce a phase hologram-like transparency which diffracts substantially all of the monochromatic light passing therethrough.

This invention further discloses that the discontinuities of the shadowgraph at the edges of the recording media which may appear in the reconstructed image are preferably removed by using a rectilinear shape to define the outer edge of the shadowgraph detecting surface while using curved perimeters to define the outer limitations of the apertured masks such that the edges of the detecting surface appear as crossed straight lines in the reconstructed image spaced from the image of the object and may be removed by appropriate iris masks in the optical reconstruction system.

BRIEF DESCRIPTION OF THE DRAWINGS

Other and further objects and advantages of this invention will be apparent as the description thereof progresses, reference being had to the accompanying drawings wherein:

FIG. 1 illustrates an embodiment of the invention in which a shadowgraph is recorded on a film as a spa-

ally coded amplitude pattern which is reproduced in reduced size on a film which is then bleached to convert the amplitude hologram to a phase hologram from which images of the object may be reproduced;

FIG. 2 is a transverse sectional view through the high energy particle detecting system of FIG. 1 illustrating the apertures in the object mask;

FIG. 3 is a transverse sectional view of the detecting system of FIG. 1 taken through line 3-3 of FIG. 1 showing the apertured system of the equidistant mask;

FIG. 4 is a transverse sectional view of the detecting structure of FIG. 1 looking toward the detecting film and illustrating the rectilinear outline of the detecting film.

DESCRIPTION OF THE PREFERRED EMBODIMENT

Referring now to FIGS. 1 and 2, there is shown a source of radiation 20 which is illustrated herein, by way of example only, as the chest of a living person. Portions of the chest area have been rendered radioactive by administering any of the well-known radioactive pharmaceuticals to the person. As is well known, selected body elements such as the liver, lung regions or blood vessels have an affinity for selected radioactive pharmaceuticals. Such an affinity varies, for example, dependent on the type of disease and the region affected by the disease.

Positioned adjacent to radiation source 20 is mask 22 consisting, as illustrated in greater detail in FIG. 2, of a plurality of curved bars 24 of material opaque to the radiation separated by spaces 26 equal in width to the width of the bars. As illustrated herein, the total open area of the mask 22 is made approximately equal to the total opaque area of the mask and may be referred to as a Fresnel zone pattern. The material of the bars 24 chosen such that the radiation from the source 20 which hits bars 24 will be absorbed but those portions of the radiation which are directed to the spaces 26 between the bars 24 will pass through.

While the mask 22 may be placed at various distances from the source 20, it is preferably positioned as close as convenient to the source 20 which is the object being detected. Hence, mask 22 may be referred to as the object mask. Mask 22 may be made, for example, by depositing a layer of lead on an aluminum plate and machining off portions of the lead to expose portions of the aluminum. Aluminum will transmit substantially all the high energy radiation impinging thereon and, hence, such exposed aluminum regions constitute radiation aperture 26.

It should be clearly understood that the thickness of the lead layer and the choice of the support plate may be made of any desired dimensions and spacing and, in general, are a function of the radioactive isotope being used. For example, with an absorption of one millicurie of either radioactive technetium or radioactive iodine, good resolution may be obtained with widths and spacings on the order of one-tenth of a millimeter to one centimeter.

The quality of the final image detected varies as a function of the length of exposure of the detector system to the patient, preferably such exposure being in the range of from one to twenty minutes and recording 10^6 and 10^{10} counts of high energy radiation particles. However, since the number of counts detected in ac-

cordance with this invention is several orders of magnitude larger than the counts detected in the pinhole or collimating absorption lens system, greater definition may be achieved.

5 The pattern formed by the bars 24 defining the apertures is a fragmented portion of a Fresnel pattern. The bars 24 extend in arcuate form to the edges of the circular ring defining the perimeter of mask 22. As illustrated herein, for purposes of clarity, only a few bars 10 and spaces are shown, and adequate results may be achieved with such a system. However, applications have found that masks with more than fifty bars and apertures are preferably used to produce high definition images from the shadowgraph formed, as illustrated 15 herein, directly on a film from a crystal scintillation layer.

The width of the narrowest spacing 26 is several orders of magnitude greater than the wavelength of the radiation. For example, if the width of the narrowest aperture is on the order of one millimeter, any radiation 20 beyond the visible range will have a wavelength many orders of magnitude less than a millimeter and, hence, any diffraction effects of mask 22 on such radiation will be substantially undetectable.

25 As illustrated herein, the pattern of bars 24 and spaces 26 forms an off-center section of a Fresnel zone pattern. More specifically, the diameter of mask 22, as shown in FIG. 2, is approximately equal to the distance from the center of the Fresnel zone pattern to the center of the mask 22. Such an offset offsets the image during the reconstruction process and is preferably great enough to separate the multiple images produced as well as to separate detecting surface edge artifacts from the desired image.

30 35 Mask 22, which may be referred to as the object mask, is supported in a housing 30 which spaces the element 22 a predetermined distance S_2 from a second spatial coding mask 32. Mask 32, which may be referred to as the intermediate or equidistant mask, is 40 formed in a similar manner to that of mask 22 and has a pattern which is the off-center section of a Fresnel zone pattern as illustrated in FIG. 3. In general, the patterns of the masks 22 and 32 are by way of example only, and any desired patterns or portions of patterns 45 which are symmetrical about axes substantially parallel to the average direction of motion of the radiation through the masks could be used. While, as illustrated herein, masks 22 and 32 are planar, they may if desired, be made as portions of spherical surfaces or cylindrical 50 surfaces or other geometric shapes.

55 As may be seen from FIG. 3, mask 32 is an off-center section of a Fresnel zone pattern identical to that of zone plate mask 22 but scaled to substantially one-half the size of zone plate 22, with the remainder of the space between the support housing 30 being filled with the portion of the aluminum backing plate covered with lead which absorbs substantially all gamma radiation impinging thereon. While the zone plate rings of mask 32 could be extended to the housing 30, the width and spacing of the absorbing rings becomes very much smaller than their thickness and no substantial additional coding would occur.

60 65 A detector system 36 is positioned at a distance S_2 from mask 32 on the opposite side thereof from mask 22 so that mask 32 is substantially equidistant between the object mask 22 and the detecting surface or holographic image plane of detector 36. Thus, a predeter-

mined point on the holographic image plane is intersected by a plurality of straight lines passing through different mask apertures of masks 22 and 32, respectively, as illustrated, for example, by point 28. Since there are a plurality of such points which are essentially arcs of circles in the holographic image detector plane, particles emitted from the object 20 will form maximum intensity by which is meant maximum number of radiation particles for that coding frequency even though object 20 is of relatively large size. It may also be seen that various other arcuate configurations may be similarly projected on the detector plane and the sum total of these forms a shadowgraph containing all the spatial frequency components of the spatial code pattern upon which the intelligence data representing the particular outline and radiation intensity of the object are superimposed. Such a pattern is an amplitude or intensity pattern and, hence, may be detected by a detector system 36.

As shown in FIG. 4, housing 30 is formed from a circular cross section to a rectangular cross section in the region where it supports the detecting system 36. It has been found that if a circular section is used for the detecting shadowgraph region, a reconstruction by optical means produces a series of circular patterns which, to some extent, interfere with or degrade the image. By the use of a rectilinear pattern, as indicated in FIG. 4, the reconstruction contains straight-line artifacts indicative of the straight-line borders of the periphery of the shadowgraph, and these intersect to form a cross with positive and negative images appearing in opposite quadrants of the cross so that by the use of an iris only one desired image may be selected and the remaining data, including the artifacts, eliminated.

The size and spacing of the masks 22 and 32 and the size of the rectilinear detector plane may be selected from a wide range of possible configurations. For work with human bodies, the following size has been found useful:

Diameter of mask 22 = 25 to 30 cm.

Effective diameter of mask 32 = 12 to 15 cm.

Rectilinear dimensions of the detecting surface = 25 cm. $\times$ 30 cm.

Spacing distances $S_1 = S_2 = 9$ cm.

The number of bars 24 which can, as a practical matter, be formed in masks 22 and 32 depends upon the thickness and material of the masking medium.

Detector system 36 is illustrated herein as being substantially planar but, if desired, may have a spherical, cylindrical or other geometric surface shape. As illustrated herein by way of example only, detector system 36 comprises a layer of film 38 sandwiched between two thin layers 40 of crystal material such as cesium iodide or calcium tungstate which produces scintillations of light when struck by gamma radiation. A backing support plate 42, preferably of light reflecting metal, is used to support the layers of crystal 40 and the film 38 positioned therebetween. The front surface of the crystal 40 on the opposite side of film 38 from the support plate 42 may also have a thin layer of light reflecting material such as an aluminum or silver surface coated thereon and, if desired, the entire package of support plate 42, film 38 and crystals 40 may be assembled as a unitary package or cassette.

In operation, gamma rays from object 20 pass through masks 22 and 32 as well as through crystal 40. Some of the gamma rays will produce scintillations of

light in one or the other of the crystal layers 40 having an intensity strength enough to partially expose the elemental areas of the film adjacent the regions of the crystals producing the light scintillation. Preferably, the 5 crystal layers 40 are made only a few millimeters thick so that definition in the pattern recorded on the film 38 is maintained in the millimeter range.

While the film 38 is preferably in a cassette, it is 10 shown herein as a portion of a roll of film 44 drawn through the crystals 40 to illustrate the process steps involved. After exposure, the film 38 is developed in accordance with conventional practice by passing 15 through a developer bath 46. Any desired degree of development can be used. Preferably, however, the film is developed sufficiently to provide maximum contrast between light and dark areas. However, different degrees of development may be used to accentuate different total intensities of the detected shadowgraph.

The film 38 is then placed in a reducing system 48 20 which may be of a conventional type in which a light source 50 emanating from a ground glass screen 52 passes through film 38 and is focused on a film 58 through a lens 54 on the opposite side of film 38 from the light source 50. The focal length of lens 54 is chosen such that the light rays converge as passing therethrough and the shadow of film 38 is projected in reduced form on film 58 to expose film 58 and reproduce a negative of the pattern developed on film 38 in reduced form on film 58.

30 In accordance with this invention, the pattern on film 58 is reduced sufficiently so that the projection of the spacing of bars 24 in the pattern recorded on film 38 will be sufficiently close to produce a substantial degree of refraction of a visible light beam passing therethrough. This has been found to produce a substantial improvement in image reproduction, both from the standpoint of image distortion and image clarity or intensity.

35 Film 58 may, if desired, also be in the form of a cassette but is shown herein in the form of a roll of film to 40 illustrate the subsequent steps of the process. Film 58 is passed through a conventional develop and bleach step illustrated at 60. The film 58 is of any desired conventional type which is developed to produce substantially the same or a greater degree of contrast as the original developed film 38 and is then bleached with any conventional film bleach to convert all of the light absorbing regions to a compound having a thickness and/or index of refraction different from the other regions of the film. In accordance with this invention, bleaching, in addition to enhancement of light transmission, is used as part of the conversion process from a shadowgraph pattern produced by noncoherent radiation into a refracting lens suitable for coherent light image reproduction in which size reduction of the 45 image is used to further enhance the quality and clarity of the reproduced image.

50 The film 58 is then used to reproduce an image of the object 20 by a coherent light reproduction system 62. System 62 may be of any desired type and, as illustrated herein, comprises a source of coherent light 64 such as a helium neon laser whose output is focused by a lens 66 through a pinhole iris 68 to remove spatial noise. Light projected through the pinhole 68 passes through 55 a converging lens 70 and then through the developed and bleached film 58 which diffracts the informational content of the picture away from the center line of the

hole and lens system 70 by a distance r_c so that it passes through a hole having a diameter in an iris 72 and appears as a reconstructed image in an image plane any desired detection system such as a ground glass screen 74. The distance of screen 74 may be varied with respect to the film 58 to produce from the pattern recorded on film 38 various slices corresponding to various distances of object 20 from the detector system

The aperture size d and its offset r_c from the iris 72 functions of the diameter of the zone plate masks 31 and 32 and the distance which the center of the zone plate patterns are offset from the center of the Fresnel zone pattern. For example, if, as illustrated, the diameter of each of the zone plates is equal to the offset of the center of that zone plate from the center of its Fresnel zone pattern, the pattern size d in the iris 72 is preferably substantially equal to the offset distance r_c from the center of the system.

As illustrated herein, the iris 72 is positioned substantially in the plane where the pinhole light from iris 68 would be focused by the lens 70 in the absence of film which may be referred to as the Fourier plane. However, other locations of the iris 72 may be used and/or other means of separating the desired image from artifacts and/or undesired images.

The image produced on screen 74 may be viewed directly and/or several pictures taken for various distances of screen 74 from the Fourier plane by means of camera 76. Alternatively, a television pickup camera may be used to view the reproduced image and/or to store images in a computer memory from which if desired, simultaneous three-dimensional views of the object 20 may be reproduced.

In accordance with this invention, individual scintillations of light from the crystals 40 will not completely expose an elemental area of the film. Thus, overlapping patterns produced by adjacent point sources will substantially all be recorded with optimum intensity and a minimum occurrence of the conditions where elemental areas of film are completely exposed so that additional scintillations of light occurring after such complete exposure go undetected.

The film 38 may be sufficiently thick for a given exposure time for such complete recording without saturation to occur since the portions of the film which are more completely exposed simply remain transparent to light in the reduction process. It should be noted that those portions which are still transparent pass the most light so that the reduced film 58 is a negative of the original film 38 causing a greater darkening of the negative 58. However, this also does not result in reduction in image intensity since substantially all of the opaque regions are substantially completely bleached and the result is simply a small average increase in the reduction of the film.

The substantial signal amplification obtained by the reduction in size of from film 38 to film 58 and the tracking allows this system to be used for direct shadowgraph recording, thereby allowing an improved definition of the image derived therefrom. The definition improvement varies as the total number of counts recorded which is a function of the time of exposure of the detecting system. Because of the large number of units available compared with the prior pinhole or illuminator type cameras, relatively thin scintillator crystals 40 may be used, thereby permitting a shadow-

graph detection definition substantially higher than those previously available. As a result, the fineness of the bar spacing of the finest bar of zone plate mask 32 may be made substantially as fine as it is practical to fabricate such structures while still projecting patterns on the detecting surface which are within the spatial frequency pass band of the detecting system. For example, with a 20 to 1 reduction in size of the hologram from film 38 to film 58, a high definition image of an object may be derived using high energy level incoherent radiation from a living tissue source, and the image constructed using coherent light in the image-forming process will be readily visible to the naked eye.

Theory of Operation

In our aforementioned copending application, the radiation emitted by the object passes in succession through a periodic half-tone screen and an off-axis section of a Fresnel zone plate. Both the half-tone screen and the zone plate are constructed so that the bars or zones are alternately transparent and opaque to the radiation. Such a system produces a coded shadowgraph strictly by geometric shadowing. The zone plate and half-tone screen are sufficiently coarse that no appreciable diffraction occurs. When the spatial frequencies are properly chosen, a strong Moire fringe pattern is formed on the shadowgraph or image plane. This fringe pattern, although formed by shadowing rather than diffraction, is closely analogous to a hologram. The original three-dimensional radiation source can be reconstructed by illuminating a transparency derived from the shadowgraph with coherent light.

The formation of the Moire fringe pattern can be better understood by considering the radiation paths. Assume that the spacing from the half-tone screen to the zone plate is equal to the spacing from the zone plate to the image plate, and that the spatial frequency in the center of the zone plate is just twice the frequency of the half-tone screen. Then there will be a point in the image plane for which the transparent zones in the center of the zone plate project onto the transparent bars of the half-tone. The radiation transmitted to this point through the center of the zone plate will be a maximum. At a nearby point for which the center transparent zones project onto opaque bars, the transmission will be a minimum. In general, a fringe pattern will be formed with both the amplitude and phase of the fringes depending on the source distribution.

In accordance with the present invention, one of the highest fringe contrasts has been obtained when the half-tone screen was a zone plate exactly twice as large as the other zone plate. The fringe amplitude is now proportional to the Fourier transform of the source multiplied by a quadratic phase factor and is closely analogous to a Fraunhofer hologram.

The two-zone-plate system has several practical advantages. The strongest fringes occur in the center of the hologram. Therefore, if either the resolution or the sensitivity of the image detector falls off at the edge of its field, comparatively little information is lost.

Because of Fourier transform property, various spatial filtering operations can easily be performed by masking the hologram plane. For example, low frequency suppression can be accomplished by masking off the center of the hologram. Also, since the fringes are macroscopic, a hologram could be examined visually and those regions where the fringe contrast is low

can be masked off. This operation is a rough approximation to matched filtering and can enhance the signal-to-noise ratio in the reconstruction.

In the aforementioned copending application Ser. No. 289,707 there is disclosed a system in which fine detail of objects, such as thyroid glands, can be readily detected with a plurality of spaced aperture structures, one of which is a portion of a Fresnel zone plate and another of which is a bar mask or half-tone screen having a constant spatial periodicity.

Such a gamma camera uses an off-axis portion of a Fresnel zone plate and a bar pattern, such that center spatial frequency of the zone plate segment, f_{zpc} , and the spatial frequency of the half tone, $f_{1/2}$, are related by the proportion, $(s_2/1/f_{zpc}) = (s_1 = s_2) (1/f_{1/2})$, where 15 s_1 is the distance from the bar pattern to the zone plate and s_2 is the distance from the zone plate to the detecting or image plane.

When the distances s_1 and s_2 are comparable to or smaller than the zone plate aperture, and the zone plate 20 rings and half-tone or bar pattern have a thickness comparable to their spacings, only those gamma rays passing fairly near normal are effective in generating an exposure on the film, due to vignetting and also to $1/R^2$ losses because diagonal rays must go farther and are 25 weaker.

It has been found that the spatial frequency match of the zone plate and bar pattern are poorly satisfied at the edges of the field both because the zone plate and half tone are not parallel and also because the zone 30 plate frequency and half-tone frequency do not match at the edges of the field. The result is field nonuniformity, the center of the field being imaged better than the edges.

In accordance with this invention, the straight bar 35 pattern is replaced by another zone plate on a scale such that spatial frequency match conditions are satisfied.

More specifically, useful results can occur when the radius of the first edge, r_1 , of each zone plate satisfies 40 the following proportion in order to obtain the frequency match

$$\frac{r_1 \text{ zp taking}}{s_2} = \frac{r_1 \text{ zp } \frac{1}{2} \text{ tone}}{s_1 + s_2}$$

Since the two zone plates are the same function (scaled appropriately), the result is the correlation function of the two identical (except for scale) patterns. If the zone plates were infinite in extent, the correlation would be an impulse, lying on a line connecting the centers of the zone plates. If we look in the "film" plane, therefore, we see the Fourier transform of the object plane.

This completes the description of the embodiments of the invention illustrated herein. However, many modifications thereof will be apparent to persons skilled in the art without departing from the spirit and scope of this invention. For example, any distortion produced in the system which is reduced by reduction in size of the film may also be reduced by other means such as correcting lenses. A variety of other spatial coding patterns other than Fresnel zone patterns may be used, and the reconstruction may be accomplished by computer using appropriate transform programs. Also, it is contemplated that this invention may be used to form images of the shadows of organs having sub-

stances which absorb gamma radiation emanating from a source external to the living organism.

Accordingly, it is contemplated that this invention be not limited by the particular details of the embodiments illustrated herein except as defined by the appended claims.

What is claimed is:

1. The method comprising the steps of: introducing radioactive material into an organ of a living body; and

forming a spatially coded pattern of high energy radiation level particles emitted from said radioactive material by selectively absorbing said high energy particles in a plurality of regions spaced along the average direction of motion of said particles through said regions by means comprising a plurality of zone plates each of which has a zone pattern of selective absorption of said particles which is substantially symmetrical about an axis substantially parallel to said average direction of motion of said particles through said zone plates.

2. The method in accordance with claim 1 including the step of:

deriving the image of said radioactive material in said organ from at least components of said spatially coded pattern.

3. The method in accordance with claim 2 wherein said step of deriving an image comprises:

spatially detecting at least a portion of said pattern.

4. The method in accordance with claim 3 wherein said step of deriving said image comprises:

converting the energy level of said particles radiated from said organ to radiation of a lower intensity than the intensity of said high energy level particles.

5. The method in accordance with claim 4 wherein said step of deriving said image comprises:

recording a spatial pattern having at least a component of said spatially coded pattern.

6. The method in accordance with claim 5 wherein said step of deriving said image comprises:

deriving said image with a beam of substantially coherent light.

7. The method in accordance with claim 6 wherein said step of deriving said image comprises:

projecting said beam of substantially coherent light through a medium whose transmissivity varies as a function of at least component of said spatially coded pattern.

8. The method in accordance with claim 1 wherein said step of forming said spatially coded pattern comprises:

spatially coding at least portions of said radiation with a plurality of space masks comprising off-center sections of Fresnel zone patterns.

9. The method in accordance with claim 8 wherein: the centers of said Fresnel zone patterns lie substantially in a line intersecting the detector plane.

10. The method in accordance with claim 1 and including: the step of spatially detecting at least portions of said high energy radiation level particles passing through said zone plates.

11. The method in accordance with claim 10 wherein: said spatially detecting step comprises converting the energy level of said particles radiating from said organ to radiation of a lower intensity than the intensity of said high energy particles.
